POWER DRIVEN HAIRBRUSH

William J. Rakocy, Clifton, and Seymour Rappoport, Rumson, N.J., assignors to Ronson Corporation, Woodbridge, N.J., a corporation of New Jersey

Filed Apr. 6, 1965, Ser. No. 84,709

Term of patent 3½ years

(Cl. D9—2)

FIG. 1 is a front elevation of hairbrush embodying our new design.

FIG. 2 is a top view of FIG. 1.

FIG. 3 is a bottom view of FIG. 1.

FIG. 4 is a right side view of FIG. 1.

FIG. 5 is a left side view of FIG. 1.

We claim:

The ornamental design for a power driven hairbrush, substantially as shown and described.
